POWER-OPERATED WINDOW REGULATOR

Edward L. Ackerman and Albert V. Crump, Detroit, Mich., assignors to Ackerman-Blaesser-Fezzey, Inc., Detroit, Mich., a corporation of Michigan

Application December 20, 1941, Serial No. 423,759

5 Claims. (Cl. 268—125)

This invention relates to power operated window regulators, the object being to provide a power actuated means for effecting movement of a window to a desired extent toward or from closed position in respect to a window opening in the body of an automotive vehicle by application of power under control of the operator including a means for releasing the window from the power actuated means to permit the window to be manually moved to fully closed or fully open position or to a position therebetween in the event the power actuated means becomes inoperative.

Other objects and features of the invention reside in the structural relationship of parts functioning in response to power application to raise or lower the window in its guide channels and including a trackway for a window supporting structure providing a guide for the window to prevent subjection of the window pressure in a direction transversely of or parallel with the plane of the window in raising or lowering the same.

These and other objects and features of the invention are hereinafter more fully described and claimed and a power operated window regulator embodying our invention is shown in the accompanying drawings in which—

Fig. 1 is an elevation partly in section showing the preferred form and structural arrangement of parts.

Fig. 2 is an enlarged elevation partly broken away showing the structural relationship of parts of the regulator mechanism.

Fig. 3 is a vertical section taken on line 3—3 of Fig. 2.

Fig. 4 is a vertical section taken on line 4—4 of Fig. 2.

Fig. 5 is a section taken on line 5—5 of Fig. 2.

Fig. 6 is an elevation partly broken away showing the position of the parts of the regulator mechanism when the window is in raised position and the mechanism is released for downward movement.

Fig. 7 is a similar view showing the position of the parts of the regulator mechanism when the window is lowered in released position.

Fig. 8 is a similar view showing the position of the parts prior to the window being lowered to the full extent.

Fig. 9 is a similar view showing the position of parts when the window reaches the lowermost locked position.

Fig. 10 is a vertical section taken on line 10—10 of Fig. 1 showing the regulator mechanism

mounted in the sash or glass recess below the window opening.

In the usual bodies of automotive vehicles the opposite vertical edges of the glass or sash rides in guide channels 2 and 3 and is movable to position to close the window opening 4 below which is the sash recess or pocket 5. Within the sash pocket is a pair of rails 6 and 7 the upper ends of which are secured to the inner wall 8 of the sash pocket and the lower ends of which are secured to the inner wall of the sash pocket. The sash or glass 1 is secured in a channel 10 to which is secured a plate 11 and the plate in turn is fixedly secured to a carriage frame or plate 12 having at each of its opposite ends a pair of grooved rollers 13, 13 and 14, 14 which ride the flanges 15 and 16 of the respective rails 6 and 7.

These rollers are provided to prevent lateral or longitudinal displacement of the plate 12 carrying the sash or glass due to pressure applied thereto by the regulator mechanism in raising or lowering the same as by means of the regulator arm 17 which is pivoted at its free end to a link 18 which in turn is pivoted at its opposite end to the plate 12 as clearly shown in Fig. 1.

As shown in Fig. 10 the plate 19 carrying parts of the regulator mechanism is secured to the inner wall 8 of the sash pocket 5 and the regulator arm 17 is on the outer face of the plate 19 and secured to a pin 20. The plate is provided with a recess 21 in the face of the plate toward the inner wall of the sash recess and in the said plate recess is a coiled spring 22 having its outer end secured to a lug 23 projecting inwardly of the plate recess, the opposite end of the spring is secured in a slot in the pin 20. The purpose of the spring 22 is to provide a counterbalance for the sash and plate 12 and the pin 20 is secured in fixed relation to the arm 17 and, by movement of the arm 17, the sash may be raised or lowered. The contiguous end of the arm 24 is pivoted on the pin 20 and the lower end of the arm 24 is pivotally connected to the end of the piston rod 25 to which is attached the piston 26 in the cylinder 27 which has one end pivoted at 28. By movement of the piston in the cylinder 27 the arm 24 is swung to the right or left to raise or lower the window. The piston 26 is moved in the cylinder 25 by exhaustion of air on one side or the other of the piston as is hereinafter more fully described.

It is necessary to lock the arms 17 and 24 in the angular relationship of parts shown in Fig. 1 so that movement of the arm 24 moves the arm 17 and correspondingly moves the sash and for

this purpose I provide a latch 29 pivoted at 30 to the arm 17. The latch 29 is formed on a radius at opposite edges 31 and 32 and in the position of parts shown in Fig. 1 has a notch at the free end to fit a pin 33 on the arm 24. Also on the said arm 24 is a pin 34 spaced from the pin 33 at a distance slightly greater than the width of the latch 29 thus permitting the latch 29 to pass between the pins 33 and 34 in lowering the window by hand. To permit the window to be lowered by hand it is necessary to first release the latch from the locked position shown in Fig. 1. For this purpose I provide a latch release mechanism as shown in Fig. 1 and on an enlarged scale in Figs. 2, 3 and 4.

It is to be observed that in raising the latch 29 from the locked position shown in Fig. 2 to the unlocked position shown in dotted lines in said figure the opposite edges 31 and 32 of the latch ride between the oppositely positioned pins 33 and 34 and thus when it is being moved it is held from material displacement. For the purpose of releasing the latch 29 from locked relation with the arm 17, as shown more clearly in Fig. 4, I provide a flanged cup 35 which is secured to the inner face of the plate 18 and the flange of the cup engages the inner, and usually fabric covered, surface of the body interior represented by the dotted line 36 in Figs. 3 and 4. In the cup member 35 is a button 37 attached to a pin 38 and the button is held outwardly of the cup 35 to position shown in Fig. 3 by the coiled spring 39 in the cup.

The inner end of the pin 38 engages the free end of a lever 40 pivoted at 41 to the upper end of the stationary plate 18 which pin passes through the ears 42 of the lever 40 at one side of the plane of the plate and providing an end 43 that engages the inturned end 44 of the bar 45 slidably mounted on the plate 18. The bar 45 is held in the position shown in Fig. 2 by a coil spring 45a. By pushing on the button 37 the lever is moved from the position shown in Fig. 3 to the position shown in Fig. 4 thereby raising the bar 45 and, due to the bar having an inturned end 46 engaging the edge 31 of the latch 29, the latch 29 is turned on its pivot 30 from the position shown in full lines in Fig. 2 to the position shown in dotted lines in Fig. 2. This frees the arm 24 from locked relation with the arm 17 thereby freeing the sash or glass to movement by hand if desired or in case the operating mechanism becomes inoperative. The bar 45 has a slot 47 for a pin 48 secured to the plate 18 and also has a slot 49 for the headed pin 50 and, when the latch 29 is raised to the position shown in dotted lines in Fig. 2 by the bar 45, the arm 17 is released from the power arm 24 permitting the window to be raised or lowered manually to a desired position and free from control by the power actuator. This is desirable in the case of emergency as for instance when the power apparatus is out of commission. The latch 29 is also spring restrained toward locked position shown in Fig. 1 by means of a bar 29a pivoted at 29b to the latch 29 and the lower end of the bar 29a has a cylindrical end portion 29c extending through an aperture in a clip 29d. A spring 29e is positioned on the said extension 29c tending to turn the latch 29 to locked position as shown in full lines in Fig. 2.

The power mechanism includes the cylinder 27 and piston 26 therein, the piston rod 28 being connected with the arm 24. The piston is movable by influence of a vacuum and means for con-

trolling the piston position is shown in Fig. 1 in which there is a valve casing 51 mounted at any convenient point within the automobile body preferably within reach of the driver of the vehicle. There is an opening 52 in one end of the casing and an opening 53 at the opposite end and within the piston casing 51 is a slide valve 54 preferably cupped at its opposite ends, as shown, and a coiled spring 55 is positioned in the cup at one end of a piston and a similar spring 56 is positioned in the cup at the opposite end of the piston. These coiled springs are of approximately equal tension and approximately center the valve in the casing. The openings 52 and 53 provide for ingress and egress of air as would be occasioned by movement of the piston by the knob 57 having a stem extending through a slot 58 and threaded in the body of the valve and whereby the valve may be manually moved in the casing in either of two directions longitudinally of the casing. On the opposite side of the casing from that occupied by the control knob is a tube 59 which is connected with the intake manifold of the engine and subject to the reduced pressure condition of the manifold. There is a conduit 60 leading from one end of the valve casing to one end of the cylinder 27 and there is also a conduit 61 leading from the other side of the valve casing to the opposite end of the cylinder 27. These two conduits 60 and 61 are normally closed to the valve casing 51 in the position of the valve shown in Fig. 1.

By moving the knob 57 and sliding the valve toward either end of the valve casing one or the other of the conduits 60 or 61 is opened to atmosphere and to the corresponding openings 52 or 53. Assuming that the valve 54 has been moved to open the conduit 61 to the slot 62, the conduit 60 would be opened to atmosphere and thus partial vacuum would be produced on the left side of the piston 26 of the cylinder 27 and air from atmosphere supplied to the right side of the piston. This would cause the piston to be moved in the direction of the arrow and turn the levers 24 and 17 to lower the window. The window may be partially or wholly lowered due to the time interval in which the valve is held in the stated position and on release thereof the valve assumes the position shown in Fig. 1 under influence of the springs 55 and 56 and the window would remain in the partially or wholly open position depending on the time period in which the valve is held in the stated position. Assuming that the window is in the down position and the piston 26 at the left hand end of the cylinder 27 the window would be raised by moving the valve in the opposite direction to open the cylinder 27 to atmosphere on one side of the piston and the reduction in pressure on the opposite side.

During the time period in which the valve 54 is held to open the conduit 60 or 61 to the space 62, air from atmosphere may flow to one side or the other of the piston 26 depending upon which conduit, 60 or 61, is open to the space 62 and the other conduit is open to atmosphere through the port 52 or 53 as the case may be.

Thus by movement of the valve in either direction the cylinder on one side of the piston is opened to atmosphere while the other side is subject to influence of partial vacuum and thus effects movement of the piston and consequent operation of the regulator mechanism. Upon movement of the glass or sash under influence of the vacuum on the piston 26 to a desired open

or closed position the valve element, by simply releasing the same to the action of the springs 55 and 56, automatically causes cessation of movement of the piston and consequently of the glass. Thus the operator may position the glass as may be desired.

It is also to be observed that only one window of the vehicle is shown as under control of the power mechanism but, in the event it is desired to control more than one window at a time, a valve member and the operating mechanism, such as indicated in Fig. 1, may be used for each window thus enabling the passengers to control the position of any window or windows therein.

It is believed evident from the foregoing description that the various features and objects of the invention are attained by the mechanism described and that the regulator for any one or more windows of an automobile is comparatively simple in construction permitting the practically instant operation of the regulator by influence of the reduced pressure condition in the cylinder 27 at one side or the other of the piston 26. It is pointed out that, on cessation of operation of the engine, a reduced pressure condition exists in the cylinder at one side or the other of the piston and may be utilized to operate the regulator mechanism in the usual manner. The described arrangement of parts thus provides a certain stored power depending upon the volumetric capacity of the cylinder which may be varied to suit specific requirements. In the event of any defect in the operating mechanism the window may be released to permit manual operation by simply pushing the button 37 or otherwise releasing the arms 17 and 24 from the locked relationship. It is further to be understood that various modifications may be made in various parts of the mechanism within the spirit and scope of the appended claims.

Having thus fully described our invention, its utility and mode of operation, what we claim and desire to secure by Letters Patent of the United States is:

1. In mechanism for raising or lowering a glass or sash in respect to a window opening in the body of an automotive vehicle having guides for the glass, a glass operating arm pivotally supported at one end on the body of the vehicle and operatively connected at the opposite end to the glass, an arm pivoted at one end to turn on an axis, a spring pressed latch element pivoted on the glass operating arm and having a notch, a pin on the said second arm engageable in said notch of the latch when the arms are in the desired angular relationship, a power element connected with the second of said arms and operable at will to turn the arms as a unit when the latch element is in engagement with the said pin, means for releasing the latch element from the pin to free the glass operating arm to turn independently of the arm connected with the power apparatus, and spring means connected with the glass operating arm providing a counterbalance for the glass.

2. In mechanism for raising or lowering a glass or sash in respect to a window opening in the body of an automotive vehicle, a glass operating arm pivotally connected at one end with the sash or glass and pivotally supported at the opposite end on the vehicle body to turn on an axis at a right angle to the plane of movement of the sash or glass, a second arm pivotally associated at one end with the pivoted end of the glass

operating arm, a power means under control of the operator connected with the free end of the said second arm, means for securing the arms together to turn as a unit on the axis of the glass

6 operating arm, said means comprising a latch pivoted at one end to the glass operating arm between its pivot point and the end thereof associated with the glass, said latch member having a notch therein at a distance from its pivot point, a pin on the second arm adjacent the pivot point thereof engageable in the notch of the latch whereby the arms may be turned in releasably fixed angular relation, said power means comprising a cylinder and piston therein, a piston rod 10 extending through one end of the cylinder and attachable to the free end of the second arm, and means associated with the cylinder for exhausting the air from one or the other end thereof and simultaneously connecting the respective 15 other ends of the cylinder to atmosphere.

3. In mechanism for raising or lowering a glass

or sash in a plane practically parallel with the plane a window opening in the body of an automotive vehicle, having a glass recess below the 20 window opening, comprising a plate secured in the sash recess at one side of the window opening, an arm having a pin at one end pivotally supported by the plate, said pin extending at a right angle to the plane of movement of the glass or 25 sash, a glass carrying element with which the opposite end of the arm is connected in a pivotal association, a spring having an end attached to the shaft and the opposite end attached to the plate to counterbalance the weight of the sash

30 and arm, a second arm pivoted on the said shaft of the first arm, means for securing the arms in fixed angular relationship comprising a latch pivotally secured to one of the arms between its pivot point and the end thereof associated with

35 the glass and detachably connected with the other of said arms between its pivot point and the free end thereof, a power means attached to the free end of the second of said arms and operable when the arms are attached to turn the arms on the 40 axis of said shaft to raise or lower the glass, and means under control of the operator for applying the power means to raise or lower the glass.

4. In mechanism for raising or lowering a glass

or sash in its plane in respect to a window opening in the body of an automotive vehicle having inner and outer spaced walls providing a recess opening to the window opening at one side thereof, a window operating arm operatively associated at one end with the glass or sash and turnable on a fixed axis at a right angle to the plane of movement thereof, a power means within the recess, a second arm connected at one end with the power means and at the opposite end turnable on the fixed axis of the first arm, a latch 50 pivoted to the first arm between the pivot point and the end thereof associated with the glass and releasably secured at its opposite end to the other arm between its pivot point and the end thereof connected with the power means, said latch providing a means for locking the arms together to permit turning of the arms as a unit by the power means, means manually operable from the interior of the vehicle to release the pivoted arms from locked relation, and means operable 55 from the interior of the vehicle to render the power means inoperative.

5. In mechanism for raising or lowering a glass or sash in respect to a window opening in the body of an automotive vehicle, a window operating arm, a link connecting one end of the said

70

arm with the glass and sash, a plate to which the opposite end of the arm is pivoted, a second arm pivoted at one end on the pivot point of the first arm, a power means connected with the opposite end of the second arm for turning the same on the axis of the first arm, a latch member pivotally connected at one end to the first arm adjacent the pivot point, the opposite end of the latch having a notch, a pin in the second arm

engageable in the notch to thereby connect the arms together to operate as a unit in raising or lowering the sash, and means operable from within the vehicle body to release the latch thereby disconnecting the said arms and permitting manual operation of the glass or sash.

EDWARD L. ACKERMAN.
ALBERT V. CRUMP.
